UNITED STATES PATENT OFFICE.

JOHN BEALBY SMITH, OF STAMFORD HILL, LONDON, ENGLAND.

STRAINER FOR TEAPOTS.

1,384,926.

Specification of Letters Patent. Patented July 19, 1921.

Application filed May 18, 1920. Serial No. 332,322.

To all whom it may concern:

Be it known that I, JOHN BEALBY SMITH, subject of the King of Great Britain and Ireland, residing at 7 Stamford Grove 5 East, Stamford Hill, in the county of London, England, have invented certain new and useful Improvements in Strainers for Teapots, of which the following is a specification.

10 My invention relates to a new or improved straining attachment for tea-pots and the like and has for its object the provision of a simple device associated with the spout of the vessel whereby a better straining effect 15 is obtained and the use of an outside strainer which is liable to become mislaid is obviated.

According to this invention I provide a perforated disk or plate which is placed within the tea-pot or the like and has a suitable clip or fastener by means of which it 20 can be readily secured to the usual perforated partition or outlet between the tea-pot body and the spout.

In carrying out my invention the perforated disk is preferably of some suitable 25 metal such as tinplate, copper or silver, the perforations being of any size according to the type of vessel to which the strainer is applied and other circumstances. This disk 30 or plate is sufficiently large to completely fit over the perforated partition or outlet before referred to, and is preferably dished or formed with a surrounding and projecting rim which thus provides a snug fit 35 against the inner surface of the tea-pot or the like and prevents the passage of tea-leaves to the spout when it is in position.

Means for readily securing the strainer in 40 position over the outlet conveniently, comprise a length of wire secured to the perforated disk or plate in any suitable manner and extending at about right angles to the plane of the disk on the same side as the rim thereon. This wire is of a springy nature 45 and after extending outwardly to the desired extent is bent over upon itself and formed with a pair of projecting shoulders and a neck in close proximity to the disk. The wire also projects beyond the opposite 50 face of the disk and is formed in the manner of a loop or the like, which is adapted to be taken between the fingers to facilitate easy insertion in the vessel when securing. To 55 effect securing, the outer end of the spring wire which is tapered is engaged in one of the usual holes or perforations in the parti-

tion or outlet. The disk is now pressed inward toward the outlet until the spring shoulders are compressed in the perforation. Continued movement will bring the shoulders clear of the perforation on the other side of the partition and as soon as they are free they will spring outward and so hold the disk in position, the neck then being situated in the perforation. The disk can be 60 readily removed for cleaning or renewal by a simple inward pull on the wire loop.

In order that my invention may be more readily understood reference is made to the accompanying drawings in which like letters of reference refer as far as possible to like parts throughout.

Figure 1 is a fragmentary view in section showing one form of the device.

Fig. 2 is a fragmentary view in section 75 showing another form of the device.

Fig. 3 is a rear view of the device seen from the interior of a tea pot.

Fig. 4 is a fragmentary view in sectional side elevation showing the device in position 80 in a tea pot.

Fig. 5 is a rear view on an enlarged scale.

Fig. 6 is a side view on an enlarged scale.

Fig. 1 shows my invention in its simplest form in which I employ a spring wire bent 85 to form a shoulder and continued for a required distance to a narrow end from which it is returned and a similar shoulder is formed to the one before mentioned and the wire bent to form a neck, and passes through 90 a perforated metal disk and terminates with a loop. The perforated metal disk which acts as a strainer is secured in any suitable way to the wire and preferably a metal clip holds the two portions of the wire together. 95 In this figure the wire referred to is formed as a loop at a^1 passing through the perforate metal disk or strainer b forming part of the neck a^2 and is then bent into a shoulder a^3 and continued to a tapered end a^4 , 100 and then returns and forms another shoulder a^5 and terminates in a straight piece a^6 completing the neck part. The free end of the wire is preferably clipped to the other part of the wire by a small band a^7 and between this band and the loop a^1 the perforated metal disk or strainer may be secured 105 in any suitable manner.

Fig. 2 shows to a slightly enlarged scale a portion of my improved device in a modified 110 form in which the loop wire a^1 to manipulate the fitting of the device to the tea-pot,

is formed separately from the spring shaped part as before described, the two wires being clipped together by the small band a^7 .

Fig. 3 shows a front elevation looking 5 from the inside of the tea-pot to the spout of my improved strainer fitted in one of the perforations in the body of the tea-pot, and

Fig. 4 shows a section of the tea-pot and 10 spout with the strainer fixed in position to cover the outlet perforations in the tea-pot communicating with the spout, and

Figs. 5 and 6 are respectively front elevation and side elevation to an enlarged 15 scale of my improved strainer in the form in which I prefer to manufacture the commercial article.

Beyond the letters of reference before referred to, the perforated metal disk or 20 strainer b , is domed for the greater part of its area and then bent over at its edges at b^1 . The body of the tea-pot is marked k and the outlet perforations k^1 communicating 25 with the spout m . The strainer b may be made of perforated metal or wire gauze to the required mesh.

I claim:—

1. In a strainer for tea-pots, a perforated disk, a spring wire closed loop on one side 30 of said disk, shoulders upon the loop adapted to engage in a perforation in the tea pot, a pointed end to said loop to facilitate engagement with the perforation in the tea pot, a handle upon the other side of said disk, said handle being connected with said loop, so that said handle and said loop form together a rigid element whereby when inserting the strainer in the tea pot, the perforation in the tea pot for receiving the 40 pointed end of the loop may be located by the sense of touch.

2. In a strainer for tea pots, a perforated disk, a spring wire closed loop on one side of said disk, shoulders upon the loop adapted to engage in a perforation in the tea pot, 45 a pointed end to said loop to facilitate engagement with the perforation in the tea pot, a neck portion in said loop adjacent the disk, a metal band around said neck, a handle upon the other side of said disk, said 50 handle being connected with said loop so that said handle and said loop form together a rigid element.

3. In a strainer for tea pots, a perforated disk, a spring wire closed loop on one side 55 of said disk, shoulders upon the loop adapted to engage in a perforation in the tea pot, a pointed end to said loop to facilitate engagement with the perforation in the tea pot, a neck portion in said loop adjacent 60 the disk, a metal band around said neck, one wire of said neck portion being movable within said band so that it can approach the other wire to allow the loop to contact, a handle upon the other side of said disk, said handle being connected with said loop, so that said handle and said loop form together a rigid element.

4. In a strainer for tea-pots, a perforated metal or wire gauze disk, a bent wire loop 70 on one side of the disk, a tapered end to this loop, shoulders on the loop and a neck between the shoulders and the disk, an extension to one limb of the wire loop which passes through and is secured to the disk, a bent 75 end to this extension on that side of the disk opposite to the loop, to form a handle, a free end on the other limb of the loop, and a metal band secured to the extended limb of the loop and encircling the free end.

JOHN BEALBY SMITH.
